FOOTWEAR HEEL

James E. Dickerson, 2400 Delaware St.,

Gary, Ind. 46407

Filed June 3, 1970, Ser. No. 23,267

Term of patent 14 years

Int. Cl. D2—04

U.S. Cl. D2—323

Fig.-1

Fig.-2

Fig.-4

Fig.-3

FIG. 1 is a side view of a footwear heel embodying my new design;

FIG. 2 is an end view of the heel of my design;

FIG. 3 is a side view taken from the opposite side of that shown in FIG. 1; and

FIG. 4 is a bottom view of the heel of my design.

I claim:

The ornamental design for a footwear heel, substantially as shown.
